Application June 20, 1932, Serial No. 618,154

25 Claims. (Cl. 250—20)

This invention relates to a new and improved receiver by means of which frequency or phase or amplitude modulated signals may be received.

Specifically, the main object of the present invention is to disclose a novel type of receiver for frequency or phase modulated signals. Briefly, in the receiver of my present invention a retarding circuit, such as a long transmission line, for example, is utilized in the conversion of the frequency or phase modulated signals to amplitude modulated signals for subsequent detection.

Certain novel features of the invention have been pointed out in the claims attached hereto. Other features are defined in my divisional application Serial No. 323,077, filed March 9, 1940.

Some methods of carrying out the present invention and some forms of circuit arrangements by means of which said invention may be carried out will be described with reference to the drawings in which:

Figure 1 shows diagrammatically a receiver devised according to and employing the principles of my present invention by means of which frequency modulated signals may be demodulated;

Figures 2, 3, and 3a show modifications of the arrangement of Figure 1;

Figures 4 and 5 show curves explanatory of the method of operating any of the receivers disclosed above when it is desired to receive phase modulated signals;

Figures 6, 7, 7a, 8, 9, and 9a illustrate circuits which may be included in the frequency modulated signal receivers of the prior figures to adapt them to efficient reception of phase modulated signals;

Figure 10 shows the correction circuits of Figures 6, 7, 7a, 8, 9, and 9a incorporated with the frequency modulation receivers of Figures 1, 2, 3, 40 and 3a; while,

Figures 11 and 11a show diagrammatically other applications of the present invention.

In Figure 1, 1 indicates an aerial system connected with a signal amplifier 2. This signal amplifier may include one or more stages of thermionic radio frequency amplifiers. The unit 2 may also include an automatic volume control where amplitude modulation is to be received. Where frequency or phase modulated signals are to be received the unit 2 may include a limiter device. Furthermore, the unit 2 may be a superheterodyne receiver which includes the features enumerated above or any combination thereof.

All that is necessary is that the frequency modulated signals appear without any alteration in

the lines 3 and 5 connected with the output of 2. A part of the energy, that is, the frequency modulated signal appearing in the output of lines 3 and 5 from the unit 2, is fed through a transformer 7, having a primary winding and a secondary winding 6, to a potentiometer resistance P1. A thermionic coupling tube A has its control electrode 9 connected with a movable point 10 on the potentiometer resistance P1 and its cathode 11 connected through a biasing battery 12 to the lower terminal of the potentiometer resistance P1. In this manner the frequency modulated signals appearing in the transformer 7 are amplified or relayed in A and appear on the anode 13 thereof and are transferred therefrom to the primary winding 14 of a combining transformer T.

Another portion of the frequency modulated energy appearing in the output of the unit 2 is fed by lines 16 to the primary winding 17 of a transformer 18 having a secondary winding 19, 20 the terminals of which are connected to the input end of a transmission line L comprising series inductance I and parallel capacity C, which serve to filter the radio frequency signal to be demodulated and also serve, as will appear more in detail hereinafter, to effect the phase thereof and permit conversion of the frequency modulated signals into amplitude modulated signals. The output terminal of the line L terminates in a damping resistance R. The desired point along the line L is connected by lead 20 to a potentiometer resistance P2. A thermionic amplifier B has its control electrode 22 connected to the movable point 23 on the potentiometer P2 and its cathode 24 connected through a biasing source 25 to the lower potential terminal of P2. The anode 26 of thermionic tube B is connected to the cathode 24 of tube B by way of the primary winding 14 of the combining transformer T. Charging potential for the anode 13 of tube A 40 and for the anode 26 of tube B is supplied from a source 28 connected in series between the cathode circuits 11 and 24, both of which are grounded, and the anodes 13 and 26 of tubes A and B respectively. A secondary winding 29 of transformer T impresses the combined signals on the control grid 30 and cathode 31 of a demodulating or rectifying tube RT. The control electrode of tube RT is biased to a characteristic at which complete demodulation takes place by means of a biasing battery 32. The demodulated signals appearing on the anode 33 of tube RT may be impressed from a jack 34 in this circuit to any utilization means, as, for instance, telephones.

In Figure 2 all of the energy relayed or ampli-

fied in the unit 2 is fed through the lines 3 and 5 to the input transformer 18 of the long transmission line L. This line L is similar in some respects to the line L of Figure 1, but differs therefrom in that this transmission line is undamped, so that reflection takes place along the line. Thus the far end of the line may be either open-ended or short-circuited. The energy from this line is fed by lead 35, connected to a tap on line 10 L, to the control grid 34 of tube A, and by line 37 to the control grid 36 of tube B so that energy may be impressed from different points on the line L to the control electrodes of the two detectors A and B. The line L is grounded at G, 15 while the cathodes 44 of the tubes A and B are also grounded at G, as shown to complete the input circuits of A and B. The control electrodes 34 and 36 are maintained at the desired biasing potential by means of a biasing source 21 connected in series with the line L.

The anode electrodes 42 and 43 of tubes A and B respectively are connected to the primary winding 45 of a combining transformer T, the output winding 47 of which is connected with a 25 utilization circuit. Charging potential for the anodes 42 and 43 of tubes A and B respectively is supplied from a source 46 connected between a tap on the winding 45 and the cathodes 44 of the tubes A and B respectively. When frequency 30 modulated signals are to be received the anodes 42 and 43 of tubes A and B respectively are connected, as shown, in push-pull relation. If amplitude modulated signals are to be received the anodes 42 and 43 of tubes A and B respectively 35 are connected in parallel relation with the input winding of the combining transformer T.

In the modification shown in Figure 3 the frequency modulated signal appearing in the lines 3 and 5, connected with the output of the unit 2, 40 is divided into three parts. The first part is fed through a transformer 7 to the input of a transmission line L. The transmission line L is damped by a terminal resistance R in a manner similar to that in which the transmission line 45 L of Figure 1 is damped. A coupling tube A has its control electrode 9 connected to a movable point 10 on the inductance of the transmission line L. The anode 13 of tube A is connected to the primary winding 14 of a combining transformer T3.

A second portion of the energy appearing in the lines 3 and 5, connected with the output of 50 2, is fed by means of lines 16 to the primary winding 17 of a transformer 18, the secondary winding 19 of which is shunted by a potentiometer resistance P1. The energy appearing across P1 or a portion thereof is fed by means of a movable tap 23 to the control electrode 24 of a coupling tube B, the anode 26 of which is connected 55 with the primary winding 14 of combining transformer T3. Charging potential for the anode 13 of tube A and anode 26 of tube B is supplied from a source 28. Biasing potential for the control electrode 9 of tube A is supplied from a source 12 connected to the line L and to ground G. Biasing potential for the control electrode 24 of tube B is supplied from a source 25 connected 60 between the cathode and control electrode 24 of tube B.

The third portion of the energy appearing in the lines 3, 5, connected with the output of the unit 2, is supplied by way of lines 30 to a coupling inductance 31 coupled with an inductance 32. The inductance 32 is in series with an inductance 33 connected with the control electrode 70 75

34 of a rectifier tube C, and also in series with an inductance 35 connected with the control electrode 36 of a rectifier tube D. The inductances 33 and 35 form the secondary inductances of a transformer T1 having a primary winding 31, one terminal of which is connected to the terminal of the secondary winding 38 of transformer T3 and to the terminal of a shunting potentiometer resistance P2, while the other terminal of primary winding 37 is connected to a movable point 40 of the potentiometer P2. The anode 42 of tube C and anode 43 of tube D are connected through windings 44 and 45 respectively of transformer T4 and through anode charging potential source 46 to the grounded cathodes of tubes C and D respectively. The secondary winding 47 of transformer T4 is connected with a utilization circuit. Biasing potential for the control electrodes of tubes C and D is supplied by a source 48 connected as shown.

In the modification shown in Figure 3a the receiver is similar in construction to the receiver of the modification shown in Figure 3, except that energy is transmitted from the output lines 3 and 5 of unit 2 through two paths or in two parts only, one of which is impressed through the damped transmission line L on to the input electrodes of coupling tube A, and the other of which is impressed co-phasally through the inductance 32 on the input electrodes of the tubes C and D. In other words, in this modification the signal is divided into two parts only for transmittal through two paths, whereas in the modification shown in Figure 3 it was divided into three parts.

In operation, as will appear more in detail hereinafter, the receiver of Figure 3a follows very closely the operation of the receiver of Figure 1.

The operation of all of the receivers disclosed in the various modifications above to receive frequency modulated signals depends upon the fact that the electrical length of a filter or a transmission line, which consists of a series of sections composed of inductive, capacitive and resistive elements in a series and/or parallel arrangement 45 or any one or a combination of said elements in said arrangement, varies with the impressed frequency.

In the following explanation a transmission line will be utilized although it will be understood that a filter, such as a high pass, low pass, band pass, band elimination, etc., may be used. If the line is a given number of wave lengths, long for a certain predetermined frequency, at a higher frequency the electrical length will be greater 55 and at a lower frequency the electrical length of the line will be less. The fact that this electrical length does change with frequency makes the phase at the output of the line change with respect to that at the input of the line if 60 the frequency of the signal transmitted by the line is varied. Consequently, if the signal impressed on the input of the line is combined with the signal at the output of the line, an adjustment of the line may be made so that the phase difference between the voltage of the signal impressed on the input of the line and the voltage of the signal appearing on the output of the line increases as the degree of frequency modulation 65 is increased. This phase difference will cause a variation in the amplitude of the resultant of the combined voltages so that an amplitude modulation is formed, which amplitude modulation is truly characteristic of the frequency modulation of the original signal. In accordance 70 75

with this invention this amplitude modulation is then detected or rectified. In other words, the transmission line or filter referred to above, in which phase shifts are produced in accordance with frequency changes of the received signal, forms part of one path to a detector. Another path, in which substantially no phase changes with variations in frequency are produced, also supplies the detector with signal energy. These two paths in, for example, Figure 3A have substantially flat amplitude versus frequency characteristics; that is to say, they pass the carrier and side band frequencies in relatively unattenuated form to the detectors in which the outputs of the paths are combined and detected.

In particular, in the receiver of Figure 1 the frequency modulated energy appearing in lines 3 and 5 in the output of the unit 2 is fed directly through coupling tube A to the combining transformer T. Simultaneously energy from 2 appearing in lines 3 and 5 is fed by way of lines 16 to transformer 18 and to the transmission line L. A lead 20, connected to a movable point on the line L, transfers energy in the proper phase to the potentiometer P₂, from whence the energy is supplied to the coupling tube B. The output energy from the line L, adjusted to the proper phase by means of the sliding tap 20, or similar means, is fed through the coupling tube B to the combining transformer T. The above transformer T, therefore, is energized by energy from A and from B.

In operation, as the frequency of the carrier changes with modulation, the energy appearing in tube B and in particular in the output circuit thereof, changes more rapidly in phase or in frequency than that from tube A, and a phase difference between the respective energies results from coupling tube A and tube B. This change in phase of the energies from the two coupling tubes results in a change in amplitude of the energy in the output circuits of the tubes A and B and in the primary winding 14 of transformer T. This amplitude change or modulation is impressed on the input circuit of detector tube C and the demodulated signal appears in the output circuit thereof, from whence it may be utilized.

While this receiver of Fig. 1 has been illustrated as having a damped transmission line, it will be understood that in this receiver the transmission line L may be undamped, or open circuited at the end. In this case the tap 20 is moved to a point on the line where the reflected wave cancels the incident wave. The operation of this modified receiver will be apparent from the description of the receiver of Fig. 3 which will be given after a description of the operation of the receiver of Figure 2.

In the receiver of Figure 2, instead of combining the energy from the output of the line L with that of the input of the line L, use is made of the fact that when the line L is open or short-circuited at the far end, a reflection of signal energy transmitted by the line occurs along the line. The combination of this reflected energy with the incident energy results in combined energy, the amplitude of which varies since the phase of the combined energies varies in the same manner as the phase of the energies combined by the coupling tubes A and B of Fig. 1 varies. When the signal frequency is changed with signal modulation a phase difference between the incident and reflected waves of line L is caused such that their resultant amplitude changes. Consequently, amplitude modulation

of the energy in the line at different points therealong is effected. By obtaining the output from the line L at two different points by way of leads 35, 37, connected at points such that at one point the incident and reflected waves are combined to increase the resultant, while at the other point two waves are combined to decrease the resultant two separate waves, with their modulation envelopes 180° out of phase, may be obtained. These two waves may be, and are, applied, as shown, to the differential detectors A and B by way of leads 35 and 37 respectively. The detected output appearing on the anode 42 of A is 180° out of phase with respect to the detected output appearing on the anode 43 of tube B. This necessitates the use of a push-pull transformer T connected to the outputs of tubes A and B. The demodulated signal may be utilized in circuit 47. Where this receiver is used to receive amplitude modulated signals the output electrodes 42 and 43 of demodulators A and B respectively must be connected in-parallel relation so that the amplitude changes add rather than oppose each other.

The receiver of Figure 2, in addition to the advantage inherent in the receiver as described in Figure 1, has an added advantage which is that the differential detectors employed in the output produce a cancellation of distortion resulting from square law detection and consequently a reduction of noise appearing with the signal in the output circuit.

The transmission line L of the receiver of Figure 2 may be undamped or open-ended, or short-circuited. The switch in the anode circuit 35 of tube B enables reception of either frequency or amplitude modulated waves, as before explained.

The operation of the receiver of Figure 3 can be readily understood after an understanding of the operation of Fig. 3a is had. The operation of the receiver of Fig. 3a will therefore be given first.

The receiver of Fig. 3a operates in a manner similar to the manner in which the receiver of Fig. 3 operates. In Fig. 3a, however, the differential detectors C and D are fed by means of a transformer T₂ co-phasally by signal energy from the output of the unit 2 appearing in lines 3 and 5 and in phase opposition by way of transformer T₁, the input of which is connected with the output of the coupling tube A, which in turn has its input circuit connected to a point on transmission line L. This combination makes the resultant amplitude modulations, fed to the detectors C and D over the two different paths, 180° out of phase. By means of the push-pull output transformer T₄, connected with the anode circuits of C and D respectively, the rectified energies appearing in the output circuits of C and D are combined in proper phase when frequency modulation is received.

The receiver illustrated in Figure 3a has all of the advantages of the receiver of Figure 1 plus all of the added advantages pointed out in connection with Figure 2. This receiver may be readily altered to receive either frequency modulated or amplitude modulated signals by merely connecting the outputs of tubes C and D in push-pull relation or in parallel relation. Switch 46 enables this change in connection to be accomplished very readily. The differential detector gives the consequent cancellation of square law detector distortion and noise reduction.

In the modification in Figure 3a the frequency modulated signal appearing in the lines 3 and 5

is transferred to the combining transformers over two channels or paths.

In other words, in Figure 3a one path, from the unit 2 to the detector system C—D, includes transmission line L, coupling tube A and transformer T₁. This path has a flat amplitude versus frequency characteristic, and freely passes all of the received signal frequencies including the carrier so that energy of side and carrier frequencies are impressed upon the secondary of transformer T₁ from the primary of T₁ in relatively unattenuated form. The secondary 33 of transformer T₁ feeds waves received from the primary of T₁ in phase opposition to like input electrodes of the detector or rectifier systems C—D. The effect of the transmission line upon the waves impressed on this path, as before explained, is to introduce shifts in phase in the wave output of the path, which shifts vary in accordance with the frequency of the waves applied to the input end of the line.

The other path, comprising conductors 30 and transformer T₂, also has a flat amplitude versus frequency characteristic for the desired signal. This other path, as is apparent from its construction, passes, from unit 2 to the detectors C—D, all of the received signal frequencies, including the carrier and side frequencies, without discrimination and with substantially no phase shift or with substantially the same constant phase shift over the entire received band of frequencies. This latter path feeds waves from unit 2 through secondary 32, connected as shown to a point electrically intermediate the ends of secondary 33, cophasally or in push-push to like electrodes of the detectors C—D.

The outputs of the two paths when combined produce a resultant which varies in amplitude. This resultant is detected by detector action of C—D to reproduce the transmitted audio, voice, or other transmitted signal.

In the arrangement shown in Figure 3 the frequency modulated energy appearing in the lines 3 and 5 is transferred to the input electrodes 45 of the detectors C and D over three different channels. A portion of the signal goes by way of transmission line L and coupling tube A to transformer T by way of transformer T₃. Another portion of the signal appearing in lines 3 and 5 goes by way of coupling tube B and transformer T₃ to coupling transformer T₁ while a third portion of the signal appearing in lines 3 and 5 goes by way of line 30 to transformer T₂ to excite the input electrodes of C and D cophasally. Also in Figure 3 the transmission line L and the coupling tubes are adjusted so that when the carrier is unmodulated the energy from the output of the line L reaching the primary winding 14 of combining transformer T₃ exactly cancels the energy reaching the winding 14 of combining transformer T₃ by way of tube B. Consequently transformer T₁ receives energy from coupling tube A and coupling tube B only when the signal is modulated. This energy from T₁ adds with the energy from T₂ on the grid or control electrode of one of the tubes C and D, and subtracts from the energy appearing from transformer T₂ on the control electrode of the other tube C or D. Consequently a differential action takes place on the input electrodes of the tubes C and D and likewise a differential detector output action appears on the output circuits of tubes C and D. The energy appearing on the anode of tube C is 180° out of phase with respect to the energy appearing on the anode of tube D and,

since the output circuits of these tubes are connected with a push-pull transformer T₄, a resultant signal appears in the utilization circuit 41. The receiver shown in this modification may be readily utilized for receiving amplitude modulated signals by merely changing the outputs of tubes C and D so that they are connected in parallel rather than in push-pull.

The receiver of Fig. 3a, like the receiver in Figure 3, includes all of the advantages of the receivers of Figures 1 and 2.

While the receiver of Figure 3a has been illustrated as utilizing a damped transmission line, it will be understood that in this receiver the transmission line L may be undamped, that is, open-circuited or short-circuited. In this case the tap 10 is adjusted to a point on the line where the reflected wave cancels the incident wave and a receiver equivalent to the receiver of Figure 3 is obtained.

When undamped transmission lines L are used with the receivers of Figures 1, 2, 3 or 3a use is made of the fact that when incident and reflected waves form on the transmission line the point of minimum and of maximum of said waves slides along the line as the input frequency is changed. Consequently when the frequency changes with signal modulation the tap is no longer on minimum point so that energy is passed to combining transformer T₁ in the instance of the undamped line arrangement of Fig. 3a, to oppose or add to the energy reaching the control electrodes of tubes C and D from transformer T₂. These two amplitude modulated frequency modulation waves are detected and combined in the transformer T₄.

The above circuits show only the fundamental features of the present invention.

In most of these circuits the use of other elements is necessary in practice. For example, volume controls, coupling tubes, and additional amplifiers may be added to the receivers in the appropriate places. Since the use of such elements will be obvious to those skilled in the art, and for the sake of simplicity, such elements have been omitted from the present disclosure.

In the receivers in which a single detector is included, or in the receivers of the type shown in Figures 2, 3, and 3a, when one detector is switched off the receiver has interference reducing properties of certain kinds of interference which are confined to one side of the wave.

Any of the receivers described above may in accordance with the present invention, be used for the reception of phase modulation waves. This is accomplished by adjusting the circuits for frequency modulation as described above and using a correcting filter at the receiver which has its output voltages inversely proportional to its input frequency so that its characteristic is as shown in Fig. 4, wherein audio frequency impressed on the input terminals of the correction circuit is plotted against voltage output.

When phase modulated signals are received on a receiver arranged to receive frequency modulated signals, the inherent difference between the frequency and phase modulated signals causes the signal output of the frequency modulated receiver to vary in amplitude directly as the frequency of the signal at the input of the frequency modulated signal receiver varies. Consequently, the audio frequency output of this receiver would be distorted and would be lacking in low frequencies. The output of the receiver instead of being the same for all audio

5 frequencies, as indicated by the dotted line of Fig. 5, would be directly proportional to the frequency of the signals impressed on the input of the receiver, as indicated by the full line of Fig. 5. In order to compensate for this distortion of the signal frequency when phase modulated signals are received on a frequency modulated signal receiver, a filter circuit or correction circuit, the amplitude of the signal frequency in the output of which is inversely proportional to the frequency of the signals impressed on the input of the circuit, as indicated in Fig. 4 of the drawings, is utilized in accordance with the present invention to adapt a frequency modulated receiver for reception of phase modulated signals. The combination of the effect of a filter circuit or correction circuit having characteristics as illustrated by Figure 4 with the effect of the inherent characteristics of a frequency modulated receiver on phase modulated signals gives an over-all characteristic such as indicated by the dotted line of Fig. 5, which is a true reproduction of the signal wave applied as phase modulation to the carrier at the transmitter.

25 If a correction filter is used with the receiver to enable it to receive and properly translate phase modulated waves it may be connected at a point following the detector, as will be pointed out in more detail hereinafter.

30 Various forms of filter or correction circuits, which will affect the signal frequencies passed therethrough in such a manner as to make the amplitude of the signals at the output thereof inversely proportional to the frequency of the signals applied to the input, may be used. Several preferred forms of correction circuits, will now be described.

35 In Figure 6 the signal frequencies to be corrected are applied to the primary winding of a transformer 50 and are impressed from the secondary winding of said transformer to the input electrodes 52, 54 of a thermionic tube 51 to energize the same in such a manner as to apply the necessary distortion or corrective effect to the signals relayed thereby. The control electrode 52 of tube 51 is maintained at the desired operating potential by means of a biasing source 55. The anode electrode 56 of tube 51 is connected through a parallel circuit comprising a resistance 57 and capacity 58 to the cathode 54 by way of a high potential charging source 59. The low frequencies of the signal potentials are emphasized by means of the capacity 58 connected across the resistor 57. The impedance of this resistance 57 and capacity 58 in parallel is high at the lower signal frequencies and low at the higher signal frequencies. The amplification factor of the tube 51, which depends upon the external impedance of its anode cathode circuit, will be high at the lower signal frequencies and low at the higher signal frequencies. The signal frequency oscillations appearing on the anode of tube 51 are impressed therefrom by way of a coupling condenser 60 to the control grid 61 of a thermionic amplifier 62. These distorted or corrected signal frequency potentials are amplified in 62 and appear in the primary winding 63 of the transformer winding 64. The corrected signal frequencies may be utilized from the secondary winding 65 of the transformer 63. In order to operate 62 at the desired point on its characteristic curve, biasing potential is supplied from the source 66 by way of resistance 67 to the control electrodes 61 of tube 62.

75 If the single distortion or correction tube 51

does not effect sufficient distortion or correction of the signal frequencies passed therethrough, a second tube, connected, in circuit and operated similar to tube 51, may be connected in cascade with 51 to apply more distortion or corrective effect to the signal. 5

In Fig. 7 the signals to be corrected are impressed on the input winding of a transformer 50 and utilized from the secondary winding 65 of transformer 63 in the same manner as in the arrangement of Fig. 6. In Fig. 7, however, no amplifier is shown connected with the correction tube 51, although it is understood that the corrected signals can be further amplified, if necessary, by connecting the output of tube 51 with the input of a thermionic amplifier. The secondary winding of the transformer 50 is connected in parallel with the potentiometer resistance 70 in order that the desired signal amplitude may be impressed on the input electrode 52 by way of the tap 71. In this arrangement the resistance R_2 is of such a high impedance to the signal current as compared to the impedance of the capacity C_2 to the signal current that the current passed through the circuits R_2 , C_2 is governed mainly by the resistance of R_2 . This makes the current through the circuit elements C_2 , R_2 constant with frequency so that the voltage across C_2 will be inversely proportional to the frequency of the applied signal due to the fact that the impedance of the condenser C_2 varies inversely as the frequency of the signals applied across the terminals thereof vary. The potentials appearing at the terminals of C_2 are impressed on the input electrodes 52, 54 of correction tube 51. 20 25 30 35

In the arrangement shown in Fig. 7a correction is applied to the signal in the same manner in which correction is applied thereto by the arrangement shown in Fig. 7. However, in Fig. 7a a second tube 51' is added for the purpose of varying the amount of distortion or corrective effect applied to the signal frequency relayed therethrough. When tube 51' is switched off full correction will be obtained by means of the tube 51 in the same manner in which correction is obtained in the arrangement of Fig. 7. With the tube 51' turned on signal potentials, the amplitude of which may be determined by the tap 71', will be applied from the parallel resistance 70' to the terminals of the resistance R_4 by way of resistance R_3 . The resistances R_3 , R_4 will affect all of the frequencies of the signal impressed thereon in like manner so that no corrective effect will be applied to the signal appearing on the input electrodes 52' of the tube 51'. Consequently, the oscillations at signal frequency, appearing on the anode 56' of tube 51' and applied therefrom to the transformer 64, will be the same for all frequencies and will represent in a normal manner the signal potentials applied at the input of the correction circuit. By moving the taps 71 and 71' along the resistances 70 and 70' the amount of corrected signal and uncorrected signal reaching the output circuit 63 can be adjusted to give the desired characteristic to the signal frequency in the output circuit, which characteristic may be somewhere between full correction of the signal and no correction. 40 45 50 55 60 65

This type of correction circuit is useful where it is desired that the transmitter radiate a combined frequency and phase modulated signal or a cross between frequency and phase modulated signal. Furthermore, such an arrangement is especially desirable where a correction circuit of

this type is used in the signal amplifier circuits of the transmitter and a second correction circuit of this type is used subsequent to the detector in the receiver receiving signals from said transmitter.

5 In the arrangement shown in Fig. 8, as in the prior arrangements, the signals to be corrected are impressed on the transformer 50 and the corrected signals are utilized from the transformer 10 64. In this arrangement, however, a different means is provided for emphasizing the lower frequencies of the signal. The value of the inductance I in series with the control electrode is so 15 chosen that its impedance to the signal frequency is high as compared to the impedance of the resistance R_5 to the signal frequencies. The inductance I then is the governing factor of the circuit and determines the intensity of the current 20 passed through the circuits I, R_5 . Since the inductance I offers a higher impedance to the higher frequencies than to the lower frequencies, the current passing through the inductance I will be inversely proportional to the frequency of 25 the impressed signals. Consequently, the voltages at signal frequency, appearing across the resistance R_5 , which are fed to the control electrode 52 of tube 51, will be inversely proportional to the frequency of the impressed signals.

30 In Figs. 9 and 9a has been shown an arrangement in which, by means of a novel circuit, a corrective effect, which is the converse of the manner in which phase modulated signals are distorted in a frequency modulated receiver, is applied to the signals. The distortion of the signal wave discussed hereinbefore is created by virtue of the fact that phase modulated waves are being received on a frequency modulated signal receiver. On the other hand, if a circuit is set up which receives frequency modulation on 35 a phase modulation receiver, a distortion is created which is the inverse of the undesired distortion obtained when phase modulation is received on a frequency modulation receiver. Obviously, if the phase modulated signal is passed 40 through these circuits in sequence the distortion effects, which are the inverse of each other, will add or cooperate to give a resultant signal which is truly representative of the initial signal to be worked with. This might seem like a devious 45 route to follow to receive phase modulation. It is not, however, and is, on the other hand, a convenient manner to receive phase modulated signals under certain conditions. The phase modulated signals are first received on a frequency modulated receiver FMR (as shown, in 50 Figures 1, 2, 3 or 3a), then converted by means of a local modulating means (transmitter) to frequency modulation, and received on a phase modulation receiver PMR as shown in Fig. 9.

55 The logical assumption may be that, since a phase modulated signal receiver is used in this correction circuit, the phase modulations should be received directly on that unit. However, there are at least two reasons for following the present course. First, the received signal output from 60 phase modulated signals received on a frequency receiver, including correcting means as illustrated in Figs. 6, 7, 7a, and 8, is different from that received directly on a phase modulation receiver 65 with respect to interference, fading, and tuning characteristics. Consequently, a corrected frequency modulation receiver (receiving phase modulated signals) will feed a certain circuit more suitably than a phase modulation receiver 70 receiving the same signals directly. Second, the

phase modulation system, including the local frequency modulation transmitter, when used for a correction circuit, in accordance with the present invention, is far more simplified than when the transmitter and receiver are at widely separated 5 points. This may be realized by an inspection of the circuit of Fig. 9a, which shows a correction circuit of this type in detail.

10 In this arrangement the signal frequencies to be corrected are applied from the detector of a frequency modulation receiver tuned to a phase modulated signal to the input terminals of a transformer 50, the secondary winding of which is connected to the control electrode 90 of an oscillation generator 91 of the dynatron type. 15 The anode 92 is connected with an oscillatory circuit 93 in which oscillations at high frequency are developed by producing a negative resistance effect in the anode cathode circuit, as disclosed more in detail in United States Patent No. 2, 20 085,739, issued July 6, 1937 to M. G. Crosby. The high frequencies which are modulated in frequency, as disclosed more in detail in the above identified application, are impressed from the circuit 93 on to a winding 94, and from winding 25 94 in opposition to the control electrodes 95 and 96 of thermionic differential detectors 98 and 100 of a phase modulation receiver. The anodes 101 and 102 of differential detectors 98 and 100 are connected in series through resistances 110 and 30 111, as shown. Charging potential for the anodes is supplied from a source 103 connected between the terminals of resistances 110 and 111 and the cathodes of tubes 98 and 100. The differential currents resulting from the signal frequencies impressed oppositely to the control electrodes of tubes 98 and 100 flow in the resistances 110 and 111. These differential currents are applied from the high potential terminals of resistances 110 and 111 to the input terminals of a radio filter circuit 40 comprising series inductances I, I' and parallel condensers C₄ connected as indicated. After passing through the filter circuits I', C₄ the differential currents flow through resistances R₅, R₆ to the control electrode 105 and cathode 106 of a 45 second dynatron oscillation generator 108. Capacities C₅ are connected between the terminals of the resistances R₅, R₆ and ground. These resistances and capacities regulate and determine the time contact of the circuit interposed between 50 the differential resistors 110, 111 and the input electrodes of the oscillation generator 108 to regulate the sensitivity and rapidity of the control effect of the differential currents on the oscillator 108. A source 109 supplies direct current 55 biasing potential to the grid electrode of 108. The differential currents from resistances 110 and 111 are superposed on this direct current potential. The output circuit 112 of the dynatron oscillation generator and modulator 108 is coupled 60 through a link circuit 113 with a transformer 114, the secondary winding 115 of which is connected in series with the control electrodes 95 and 96 of differential detectors 98 and 100 so that the carrier frequencies developed in 112 and 65 modulated by the differential currents in 108 are applied cophasally to the control electrodes of the differential detectors 98 and 100. This entire arrangement of the differential detectors and the frequency control means for the supplemental 70 modulator and generator 108 is, in many respects, similar to the automatic frequency control device disclosed in United States Patent No. 2,065,565 issued Dec. 29, 1926, to M. G. Crosby. The detected signals appearing in the anodes of differ-

ential detectors 98 and 100 are applied by way of coupling condensers 116 and 117 to the terminals of series resistances 118, 119 and from the terminals of said resistances to the control electrodes of a pair of amplifier tubes 120 and 121 having their anodes connected through the primary winding 63' of a transformer 64'. This phase modulation receiver, including the differential detectors 98 and 100, the frequency controlled oscillator means 108, and the repeaters 120 and 121, impart to the signals, which modulate the frequency of the carrier impressed thereon, a distortion which is the converse of the distortion given to the phase modulated signal in the frequency modulated receiver. The two distortion effects add to provide in the output of transformer 64' a signal which is truly representative of the signal impressed on the original phase modulated wave. The corrected signal frequencies may be utilized from the secondary winding 65' of this transformer.

Any one of the correction circuits illustrated in Figs. 6, 7, 7a, 8, 9, and 9a, may be utilized with the frequency modulated receivers of Figs. 1, 2, 3, and 3a, as indicated in Fig. 10, in which 1 is the aerial system, 2 is a signal amplifier of any type, and 80 indicates any one of the phase or frequency or amplitude receivers of Figs. 1, 2, 3, and 3a connected to 2 by way of leads 3 and 5. The correction circuits of Figs. 6, 7, 7a, 8, 9, and 9a may be incorporated in the receivers by merely connecting the primary winding of the transformer 50 of any of the correction circuits to the output terminals of the detectors R, T, AB, or CD of the receivers of Figs. 1, 2, 3, and 3a respectively. When the receivers are so modified phase modulated signals may be received thereon without distortion.

It will be obvious to the reader that the present invention is of particular importance for several reasons. Many frequency modulated receivers of various types are in use today. These receivers may, as described above, be utilized to give undistorted phase modulation reception by merely connecting therewith a correction circuit as disclosed above. Further, such a receiving system as disclosed above also lends itself admirably to diversity reception systems, as indicated in Fig. 11.

In Fig. 11 a plurality of aerial systems, X, Y, and Z may be coupled through radio frequency amplifiers X₁, Y₁, and Z₁ to the amplifier and/or combining unit indicated diagrammatically at 2. The units X₁, Y₁, and Z₁ may be heterodyne receivers which reduce the signals to an intermediate frequency for transmission over the lines to the unit 2. The unit 2 may include the radio frequency amplifiers or a heterodyne receiver in addition to the combining unit. The output of the unit 2 is, as indicated, connected by way of leads 3 and 5 to a frequency or phase or amplitude modulated signal receiver 80 of the type shown in any of the Figures 1, 2, 3, and 3a.

When the unit 80 includes a frequency modulation receiver, a correction circuit, as illustrated in Figs. 6, 7, 7a, 8, 9, or 9a, may be included in the unit 80 shown dotted between the receiver 80 and the output jack.

Furthermore it will be obvious that the present invention is especially applicable to diversity receiver systems in which automatic volume control for the radio frequency amplifiers is provided. Such a system then might take the form of the arrangement disclosed diagrammatically in Fig. 11a. In this arrangement a direct cur-

rent component is derived from the output of the demodulation tube or rectifier in 2 and fed back to the radio frequency amplifiers of the units X₁, Y₁, and Z₁ where it is used to determine the biasing potential applied to the tubes therein thereby determining the amplification factor of the tubes. The arrangement is such that the desired relation between received signal strength and biasing potential may be maintained. A more complete understanding of the details of this volume control may be had by referring to Moore U. S. Patent #1,849,632, and Crosby U. S. Patent #1,835,761.

Although in the arrangements of the present invention, as illustrated above, in general tubes of the triode type, except for the dynatrons of Figs. 9 and 9a, are used, it will be understood that said circuits may obviously be modified to use any of the types of tubes in general use today. For example, tubes of the screen grid type may be inserted in place of the triodes illustrated without departing from the spirit of the present invention. Furthermore, other tubes also may be utilized, the only provision being that the tubes have the desired operating characteristics.

Having thus described my invention and the operation thereof, what I claim is:

1. A frequency modulated signal receiving means comprising, signal absorbing means, signal amplifying means connected therewith, thermionic detecting means comprising a pair of thermionic tubes having their input electrodes connected in symmetrical circuits, a plurality of transmission channels each connected with the output circuit of said amplifying means, at least one of said transmission channels having an electrical length greater than the electrical length of the other channels, which electrical length varies as the frequency of the signals impressed thereon, means for coupling the output circuit of one of said transmission channels in opposition to like control electrodes of said tubes, and means for coupling the output of another of said transmission channels co-phasally to like control electrodes of said tubes.

2. A frequency modulated signal receiving means comprising, signal absorbing means, signal amplifying means connected therewith, thermionic detecting means comprising a pair of thermionic tubes having their input electrodes connected in symmetrical circuits, a plurality of transmission channels each connected with the output circuit of said amplifying means, at least one of said transmission channels comprising series and parallel inductances and capacities of such value that the phase of the output of said channel varies as the frequency of the transmitted signal therein varies, means for coupling the output of said last named transmission channel in opposition to the control electrodes of said tubes, and means for coupling another of said transmission channels co-phasally to the control electrodes of said tubes.

3. Means for changing frequency modulated signals into frequency and phase modulated signals which are characteristic of the frequency modulated signals and changing the phase modulated signals into characteristic amplitude modulated signals comprising, signal responsive means, rectifying means comprising a pair of thermionic tubes having their input electrodes connected in symmetrical circuits, a plurality of transmission channels each connected with the output circuit of said signal responsive means, at least one of

- said transmission channels having an electrical length greater than the electrical length of the other channels, which electrical length varies as the frequency of the signals impressed thereon, 5 means for coupling the output circuit of said one transmission channel in opposition to the control electrodes of said tubes, and means for coupling another of said transmission channels co-phasally to the control electrodes of said tubes.
- 10 4. Means for demodulating high frequency oscillations modulated in frequency at signal frequency comprising, signal receiving means, demodulating means, a plurality of transmission channels coupled to said receiving means on the 15 one hand and to said demodulating means, on the other hand, said transmission channels each terminating in thermionic tubes coupled to said demodulating means, said transmission channels being of different electrical length, one of said 20 transmission channels comprising series inductances and parallel capacities of such value as to insure that the phase of the oscillations reaching the thermionic coupling tube at the terminal of said channel shifts in a manner characteristic 25 of the changes in frequency of the received signal, and the ratio of the input to output amplitudes of the band passed by said channel is constant another of said channels having a small reactance whereby said oscillations reaching the thermionic coupling tube at the 30 terminal of said channel are of substantially the same phase and frequency as the oscillations at the input of said channel.
5. A receiver for receiving desired signals transmitted as frequency modulations of a carrier wave comprising means for picking up a carrier wave modulated in frequency in accordance with a desired signal, means for heterodyning the picked up waves to a band of intermediate frequencies, a first coupling means for feeding a portion of the heterodyned waves including the intermediate carrier and all side frequencies to a rectifier, a second coupling means arranged to feed another portion of the heterodyned waves 40 including the intermediate carrier and all side frequencies to said rectifier, each of said coupling means being arranged to transmit therethrough to said rectifier the mid-frequency or intermediate carrier of the heterodyned band of 45 frequencies undiminished in value with respect to and having a value at least as great as the side frequencies of the intermediate frequency band, only one of said coupling means introducing a phase shift, which phase shift varies with the 50 frequency of the waves fed therethrough to said rectifier, whereby said rectifier is enabled to rectify amplitude variations of the resultant of said waves brought about by the combination of the phase shifted energies passed through said one 55 coupling means and the relatively unshifted waves passed through the other coupling means.
6. In a system for demodulating oscillations modulated in length in accordance with signals, signal collecting means, thermionic rectifying means, a plurality of transmission channels of 60 different effective electrical length, each having an input terminal coupled to said collecting means and each having an output terminal connected with the input electrodes of a thermionic 65 coupling tube, there being a coupling tube for each channel and a circuit coupling the output electrodes of all of said thermionic tubes to said rectifying means, one of said transmission channels comprising series inductances and parallel 70 capacities so related and selected that the electrical

length of said channel varies as the length of the applied oscillations vary.

7. A radio receiver for receiving and translating a frequency modulated carrier wave of substantially constant amplitude comprising, a pair 5 of rectifier systems having input and output electrodes, means for feeding energy of carrier wave frequency and energy of side band frequencies derived from the received frequency modulated wave through a transformer in phase opposition 10 to like input electrodes of said rectifier systems, said feeding means passing energy of carrier wave frequency in phase opposition to said like electrodes undiminished in amplitude relative to the amplitude of energy of side band frequencies 15 fed thereto, and additional means for feeding received wave energy of substantially all frequencies including side band frequencies and wave energy of carrier wave frequency undiminished in strength relative to the strength of the side 20 frequencies, in relatively phase displaced relation, with respect to the energy passed by said first feeding means, and in push-push through a point electrically intermediate the ends of the secondary of said transformer to said like input 25 electrodes and means for connecting the output electrodes of said rectifier system in phase opposition.

8. A radio receiver for receiving and translating a modulated carrier wave of substantially 30 constant amplitude comprising a pair of rectifiers having their cathodes connected together and their anodes connected in phase opposition, means for feeding wave energy derived from the carrier and its side bands through a transformer 35 in phase opposition to like control electrodes of said rectifiers, said feeding means passing energy of carrier wave frequency in phase opposition to said like electrodes undiminished in amplitude relative to the amplitude of side band energy 40 fed thereto, and additional means for feeding received wave energy of all frequencies including side band frequencies and carrier wave frequency undiminished in form, in relatively phase displaced relation, with respect to the energy 45 passed by said first feeding means, and in push-push to like electrodes of said rectifiers.

9. A receiver for receiving and translating carrier frequency waves of constant amplitude modulated in accordance with a signal comprising a 50 transmission line having inductance and capacity, means for impressing said carrier frequency waves on said line, a pair of detectors each having an anode, a cathode and a control electrode, means connecting said cathodes together, means 55 connecting said anodes in phase opposition, and means effectively coupling said control electrodes to points on said line whereat the voltages of said impressed waves are displaced in phase.

10. A receiver for receiving and translating 60 carrier frequency waves of constant amplitude modulated in frequency in accordance with a signal comprising a transmission line of substantial electrical length having inductance and capacity, means for impressing said carrier frequency waves on said line, a pair of detector systems each having an input electrode and an output electrode, means connecting said output electrodes in phase opposition, and means effectively coupling said input electrodes to different points 70 on said line whereat the voltages of said waves impressed thereon are not in phase.

11. A receiver for receiving and translating waves which are frequency modulated in accordance with a desired signal comprising means 75

- for picking up waves so frequency modulated; a pair of rectifier systems each having an input electrode and an output electrode; means connecting said output electrodes in phase opposition; means, including a transformer having a primary winding connected to said pick-up means and a secondary winding connecting said input electrodes in phase opposition, operating to apply frequency modulated waves of substantially constant amplitude and of a phase which varies as the frequency of the received waves vary to said input electrodes in phase opposition and means connected to said pick-up means for applying through a tap on said secondary winding, frequency modulated waves of substantially unvaried phase and amplitude in push-pull relation to said input electrodes, whereby the resultant produced by the constant amplitude waves of varied and substantially unvaried phase 10 is of variable amplitude and is rectified by said rectifier systems to produce the desired signal across the output electrodes of said rectifier systems.
12. In a modulated wave demodulating means, wave amplifying means, an output circuit coupled to said amplifying means, an undamped transmission line comprising series inductive reactances and parallel capacitive reactances, a pair of thermionic tubes each having a control grid, a cathode and an anode, a connection between a point on said line and the cathodes of said tubes, a connection between the control grid of one of said tubes and a point on said line at which the incident wave and reflected wave combine to increase their resultant, a connection between the control grid of the other of said tubes and a point on said line at which the incident wave and reflected wave combine to decrease their resultant, a circuit connected to the anodes and cathodes of said tubes, and signal utilizing means connected to said circuit.
13. A wave demodulating means as recited in claim 12 in which said last named circuit connects the anodes of said tubes in push-pull relation.
14. A demodulating means as recited in claim 12 in which said last named circuit connects the anodes of said tubes in parallel.
15. The method of demodulating frequency modulated electrical waves by means of a plurality of transmission media the electrical length of one of which varies in a manner characteristic of the variations in frequency of the modulations on the oscillations which includes the steps of, setting up oscillations characteristic of said frequency modulated waves, passing all frequencies including the carrier frequency of said oscillations through each of said media, combining the energy passed through said media in phase displaced relation, and rectifying the combined energy to render the signal, said transmission media passing therethrough all frequencies including the carrier frequency without substantial attenuation so that said media have substantially flat amplitude versus frequency characteristics over the frequency range of the frequency modulations.
16. The method of demodulating frequency modulated electrical waves by means of a plurality of media the electrical length of one of which at least varies as the wave frequency varies to add to said variations additional variations in phase or frequency characteristic of the said signal frequency variations which includes the steps of, collecting said frequency modulated wave energy, passing a portion including the carrier and all side frequencies of said wave energy through each of said media, combining energy passed through said media in displaced phase relation to obtain wave energy the amplitude of which varies in accordance with the signal frequency variations on said collected wave energy, and rectifying the combined energy to render the signal, said media freely passing all received side frequencies and the carrier frequency there-through.
17. A receiver for frequency modulated waves comprising means for picking up frequency modulated waves, means for heterodyning the picked up waves to a convenient beat frequency, a pair of detectors each having an anode, a cathode and a grid, the cathodes of said detectors being connected together, the anodes of said detectors being connected in phase opposition, means including a coupling transformer for feeding beat frequency energy varying in phase as a function of frequency, in phase opposition to the control grids of said detectors, said coupling transformer passing all frequencies of the beat frequency energy including the carrier frequency in substantially undiminished form, and means for feeding beat frequency energy between said cathodes and a point intermediate the ends of the secondary of said transformer coupling means for feeding waves of all frequencies in relatively undiminished form in push-push to the control grids of said rectifiers.
18. In a receiver for wave energy the frequency of which is modulated in accordance with a desired signal, means constituting a plurality of paths for said signal frequency modulated waves, each of said paths having a substantially flat amplitude versus frequency characteristic thereby freely passing the carrier frequency and all the other frequencies of the received band, means for receiving frequency modulated waves including waves of carrier frequency and impressing them on said paths, a combination of reactance elements in one of said paths, and means for combining and rectifying wave energy including carrier frequency energy freely transmitted by and through each of said paths, said path containing the combination of reactance elements producing a change in phase at its output end, without substantial change in amplitude of the waves freely passed thereby, which change in phase varies in accordance with the changes in frequency of the waves applied to the input end of said path.
19. The method of receiving a frequency modulated wave which consists in deriving from said wave a plurality of currents each of said currents varying in frequency, an amount proportional to the amplitude and at a rate equal to the frequency of the transmitted signal, passing the currents of varying frequency including the carrier frequency through two paths having different characteristics of transmission for said currents, one of said paths having a characteristic such that there is a greater phase shift at its output end with variations in frequency applied to its input end than that produced at the output end of the other path with the same variations in frequency at its input, said paths attenuating the carrier frequency and side band frequencies substantially equal amounts and combining in a detector an output current from each path, each output current including substantially unattenuated carrier frequency and

side band frequency currents, to recreate the transmitted signal.

20. The method of receiving a frequency modulated wave which consists in deriving from said wave a plurality of currents, each varying in frequency in accordance with the variations of the transmitted signal, passing all of said currents in substantial amounts through two paths, causing one of said paths to change the phase of the current passing therethrough with respect to that of the other, the amount of phase change produced varying with the frequency of the received wave and combining the output currents of these two paths in a detector to recreate the transmitted signal, each of said paths having a substantially flat amplitude versus frequency characteristic over a band of frequencies so as to freely pass to said detector, side band frequency wave energy and wave energy of carrier frequency in unattenuated form relative to wave energy of side band frequencies.

21. A receiver for frequency modulated waves comprising means for picking up frequency modulated waves, means for heterodyning and limiting the picked up waves to a convenient, substantially constant amplitude variable frequency beat frequency, a pair of detector systems each having an input and an output electrode, the output electrodes of said detector systems being connected in phase opposition, a first circuit including a transformer having its secondary coil connected in phase opposition to said input electrodes for feeding beat frequency energy in phase opposition to the said input electrodes, said circuit passing all frequencies of the beat frequency energy including the carrier frequency without amplitude discrimination to said input electrodes but with a phase shift at the output end of said circuit which varies with the frequency of the waves applied to the input end thereof, and means for feeding frequency modulated beat frequency energy to a point effectively intermediate the ends of the secondary of said transformer thereby exciting said input electrodes cophasally with all frequencies of the frequency modulated beat waves an amount which is substantially constant over the entire range of frequencies of the beat frequency, frequency modulated waves.

22. In a system for receiving wave energy the wave length of which has been modulated in accordance with voice signals to produce wave length modulated wave energy covering a predetermined band of frequencies and for converting said wave length modulations to substantially corresponding amplitude modulations of wave energy and demodulating the same, means responsive to wave length modulated wave energy, means coupled with said last named means for amplifying the wave length modulated wave energy, modulation potential utilizing means, amplitude modulated wave demodulating means having an input and having an output coupled to said modulation potential utilizing means, a first coupling between said amplifier and said input of said demodulating means for impressing on said input, voltage output from said amplifier without appreciable shift of phase or variation in amplitude with respect to frequency within said band of frequencies, and a second coupling between said amplifier and said input of said demodulating means comprising reactance for impressing, on said input, voltage output from said amplifier substantially without variation of amplitude with respect to frequency within said band of frequencies but with a phase which varies with the

frequency of the received wave energy, said first and second couplings including means for combining their outputs, prior to demodulation, to produce a resultant varying in amplitude which resultant is demodulated by said demodulating means to reproduce said voice signals.

23. In a system for receiving wave energy the length of which has been modulated in accordance with voice signals modulating the same, means responsive to wave length modulated wave energy, means coupled with said first named means for reducing the frequency of the wave length modulated wave energy, means coupled with said second named means for amplifying the wave length modulated wave energy of reduced frequency, modulation potential utilizing means, amplitude modulated wave demodulating means having an input and having an output coupled to said modulation potential utilizing means, a first coupling between said amplifier and said input of said demodulating means for impressing, on said input, voltage output from said amplifier substantially without shift of phase or variation in amplitude with respect to frequency within said band of frequencies, and a second coupling between said amplifier and said input of said demodulating means comprising phase shifting means for impressing, on said input, voltage output from said amplifier substantially without variation of amplitude with respect to frequency within said range but with a phase which varies with the frequency of the received wave energy, said first and second couplings including means for combining their outputs to produce a resultant of variable amplitude which resultant is demodulated by said demodulating means to reproduce said voice signals.

24. In a system for receiving and demodulating wave energy modulated in length or in amplitude in accordance with signalling potentials, a first demodulator of the electron discharge tube type having an input and having an output, a second demodulator of the electron discharge tube type having an input and an output, a first means coupling the inputs of said first and second demodulators in phase opposition, means for impressing said modulated wave energy on said first means to thereby excite said inputs in phase opposition by said wave energy, a second means coupling said inputs of said first and second demodulators in parallel or cophasal relationship, means for impressing said modulated wave energy on said second means to thereby excite said inputs cophasally by said wave energy, and a switch cooperating with the outputs of said first and second demodulators for coupling said outputs in phase opposition when said wave energy impressed on said first and second means is wave length modulated and for coupling said outputs cophasally when said wave energy impressed on said first second means is amplitude modulated.

25. In a system for receiving and demodulating wave energy modulated in length or in amplitude in accordance with signalling potentials, means for heterodyning said modulated wave energy to a lower frequency, a first demodulator of the electron discharge tube type having an input and having an output, a second demodulator of the electron discharge tube type having an input and an output, a first means coupling the inputs of said first and second demodulators in phase opposition, means coupled to said heterodyning means for impressing said modulated wave energy of reduced frequency on said first means to thereby excite said inputs in phase opposition by said

modulated wave energy of reduced frequency, a second means coupling said inputs of said first and second demodulators in parallel or cophasal relationship, means coupled to said heterodyning means for impressing said modulated wave energy of reduced frequency on said second means to thereby excite said inputs cophasally by said wave energy of reduced frequency, and a switch co-operating with the outputs of said first and second

demodulators for coupling said outputs in phase opposition when said wave energy of reduced frequency impressed on said first and second means is wave length modulated and for coupling said outputs cophasally when said wave energy of reduced frequency impressed on said first and second means is amplitude modulated.

MURRAY G. CROSBY.
